UNITED STATES PATENT OFFICE.

FREDERICK J. DE WITT, OF AUBURN, NEW YORK, ASSIGNOR OF ONE-HALF TO GEORGE M. HAMILTON, OF AUBURN, NEW YORK.

SOLDERING-IRON HEATER.

SPECIFICATION forming part of Letters Patent No. 761,584, dated May 31, 1904.

Application filed May 6, 1903. Serial No. 155,838. (No model.)

To all whom it may concern:

Be it known that I, FREDERICK J. DE WITT, a citizen of the United States, residing at Auburn, in the county of Cayuga and State of New York, have invented certain new and useful Improvements in Soldering-Iron Heaters; and I do declare the following to be a full, clear, and exact description of the invention, such as will enable others skilled in the art to which it applies to make and use the same, reference being had to the accompanying drawings, and to the figures of reference marked thereon, which form a part of this specification.

This invention relates to soldering-iron heaters, and has for its object to provide improved means for concentrating the heat about the soldering-iron to more quickly and uniformly heat the same. It is furthermore designed to have the invention embodied in the form of an attachment adapted for convenient application to and removal from any common or ordinary type of heater and also adapted for supporting the iron in proper relation with respect to the torch or burner of the heater.

With these and other objects in view the present invention consists in the combination and arrangement of parts, as will be herein-after more fully described, shown in the accompanying drawings, and particularly pointed out in the appended claims.

In the drawings, Figure 1 is a side elevation of a soldering-iron heater having the device of the present invention applied thereto and showing a soldering-iron supported in position to be heated. Fig. 2 is a plan view thereof. Fig. 3 is a plan view of the top of the present invention. Fig. 4 is a rear elevation showing the brackets for support of hood and soldering-iron and the inside of the hood. Fig. 5 is a side elevation showing the adjustability of the bracket for the support of the iron. Fig. 6 is a sectional view of the hood, taken on line *a a*, showing the torch, brackets, and the direction of the flame in the hood, which is designated by the arrows.

Like characters of reference designate corresponding parts in all of the figures of the drawings.

For an adequate understanding of the application and operation of the present attachment there has been shown in the drawings a solder-iron heater 1, which may be of any common or preferred type, the one shown having a fuel-supply pipe 2, rising from the top of the can or body which contains the hydrocarbon fuel, usually gasolene, with a burner or torch 3 projected laterally from the top of the supply-pipe. Beneath the torch and carried by the pipe 2 is an ordinary drip-cup 4 to contain a small amount of fuel for initially heating the torch or burner.

In carrying out the present invention it is designed to confine the flame about the torch or burner, preferably by means of a substantially cylindrical hood or casing 5, which embraces the torch and is provided with an outer or forward closed end and a rear open end. This hood is braced or stiffened by means of a metal bar or rib 6, riveted or otherwise secured externally to the bottom or lower side thereof, and is provided at its rear end with a pendent ear or projection 7.

For the support of the hood there is a bracket 8, the forward portion of which is extended laterally to form an arm 9, having an outer terminal pendent ear 10, which is connected to the ear or projection 7 of the hood by means of a screw 11. The opposite rear end of the bracket is also projected laterally in the same direction as the arm 9 and is bent into a loop or collar 12, adapted to embrace the rear portion of the torch or burner, there being a suitable adjusting-screw 13 piercing the rear terminal of the bracket and the adjacent portion thereof to snugly bind the loop or collar upon the torch.

It will be understood that the hood-supporting bracket is at one side and slightly below the torch, and at the opposite side of the latter is a soldering-iron support, consisting of a bracket 14, applied to the ear 7 of the hood and pierced by the screw 11, from which the bracket inclines upwardly and rearwardly to a point above the torch, where it is directed laterally to form an arm 15, extending across the torch and in rear of the hood.

In heating a soldering-iron (indicated at

16) it is thrust into the hood through the rear open end thereof and rested upon the bottom lining of the hood, the handle or shank portion of the iron resting across the arm 15 as 5 a support to hold the iron in its proper relation with respect to the torch. As best indicated in Fig. 1 of the drawings, it will be noted that the hood fits close up about the lower side of the torch, so as to give considerable space between the top of the torch and the top of the hood for the reception of the iron and also to direct and confine all of the flame into intimate contact with the iron. While not absolutely necessary, it is preferred to provide the hood with some heat-non-conducting lining 17—as, for instance, asbestos—to retard radiation.

For convenience in adjusting the attachment in accordance with different conditions 20 the hood and the bracket 14 may be adjusted to different angles upon the main bracket 8 through the medium of the screw 11.

Having thus described the invention, what is claimed, and desired to be secured by Letters 25 Patent, is—

1. In a soldering-iron heater, the combination with the laterally-projecting torch, of a hood closed at its front end and open at its rear, means for supporting the hood in a position so that the flame from the torch is delivered into the open rear end of the hood and a space is formed for the entrance of the soldering-iron between the end of the torch and the top wall of the hood, and means for 30 supporting the soldering-iron handle above the torch so that the iron is held in position before the flame.

2. In a soldering-iron heater, the combination with the laterally-projecting torch, of a hood closed at its front end and open at its rear, means for supporting the hood from the torch in a position so that the flame from the torch is delivered into the open rear end of the hood, and a space is provided for the entrance 35 of the soldering-iron between the end of the torch and the top wall of the hood, and means for supporting the soldering-iron handle above the torch so that the iron is held in position before the flame.

5. In a soldering-iron heater, the combination with a torch, of a flame-confining hood arranged with relation to the said torch, means for adjusting the hood relatively to the torch, and means adjustably secured to the hood for 50 adjustably supporting the iron within the hood relatively to the torch.

4. In a soldering-iron heater, the combination with an upstanding feed-pipe and a torch projected laterally therefrom, of a heat-confining hood supported upon the heater, one end of the hood being closed and the opposite end open for the reception of the iron, and means adjustably secured to the hood for 55 supporting the iron therewithin relatively to the torch.

5. The combination with an approximately horizontally arranged torch, of a flame-confining hood mounted thereon and having an adjustable movement in a vertical plane with relation thereto.

6. The combination with an approximately horizontally arranged torch, of a flame-confining hood spaced therefrom, said hood having a vertically-adjustable movement with relation to the torch, and means adjustably secured to the hood for adjustably supporting the iron therewithin.

7. The combination with an approximately horizontal torch, of a flame-confining hood spaced therefrom, the hood having one end closed and its opposite end open and having a vertically-adjustable movement with relation to the torch, and means adjustably secured to the hood for adjustably supporting the iron therewithin relatively to the torch.

8. In a soldering-iron heater, the combination with an upstanding feed-pipe and torch projected laterally therefrom, of a heat-confining hood supported upon the torch and having a vertically-adjustable movement with relation to the torch, the forward end of the hood being closed and the rear end being open for the reception of the iron, and an iron-support mounted upon the heater and adjustably disposed in the rear of the hood to 95 adjust the iron relatively to the torch.

9. A soldering-iron heater, embodying a hood, a main supporting-bracket and an iron-supporting bracket, having their forward ends connected to the hood, one of the brackets being inclined upwardly and rearwardly and provided with an iron-supporting arm.

10. In a soldering-iron heater, the combination with an upstanding feed-pipe and torch, of a heat-confining hood, a supporting-bracket having connection with the hood and the torch of the heater, and another bracket having adjustable connection with the hood and provided with an iron-supporting arm.

11. In a soldering-iron heater, the combination with an upstanding feed-pipe and torch, of a heat-confining hood having one of its ends closed and at its opposite end open, a bracket for supporting the hood upon the torch of the heater, a bracket for supporting the soldering-iron with relation to the open end of the said hood, and a single means coöperating with the said brackets and the hood to permit of an adjustment of the said hood and iron-support.

12. In a soldering-iron heater, the combination with an upstanding feed-pipe and torch, of a heat-confining hood having one of its ends closed and its opposite end open, a bracket for supporting the hood upon the torch of the heater, means for adjustably securing the bracket to the said torch, a bracket for supporting the soldering-iron with relation to the open end of the said hood, and a single means coöperating with the said brackets and

the hood to permit of an adjustment of the latter and the iron-support.

13. In a soldering-iron heater, the combination with an upstanding feed-pipe and a torch, of a flame-confining hood suspended from the torch of the heater, said hood being capable of a vertical and substantially horizontal adjustment with relation to the torch, and means for adjustably supporting the soldering-iron 10 within the hood relatively to the torch.

14. A soldering-iron heater, embodying a hood which is closed at its forward end and open at its rear end and provided with a pendant ear, a main supporting-bracket and an 15 iron-supporting bracket having their forward

ends applied to the ear, a connecting-screw piercing the forward ends of the two brackets and the ear, both brackets being projected in the rear of the hood, the rear end of the main bracket having a laterally-disposed adjustable collar, and the other bracket being inclined upwardly and rearwardly and provided with a lateral iron-supporting arm. 20

In testimony whereof I affix my signature in presence of two witnesses.
